UNITED STATES PATENT OFFICE.

HYMAN MAIMIN, OF NEW YORK, N. Y., ASSIGNOR TO MAIMIN SPEED CONTROL CORPORATION, A CORPORATION OF NEW YORK.

MOUNTING FOR SEWING-MACHINE MOTORS.

Application filed December 10, 1925. Serial No. 74,494.

This invention relates to motor drives for sewing machines and more particularly to means for mounting the motor in driving relation to the machine.

It is common practice to drive sewing machines by means of small electric motors externally mounted adjacent the hand-wheel of the machine, driving either through frictional contact with the periphery of the hand-wheel or by means of a belt. Such drives when used in connection with commercial machines can be bolted to the table or otherwise permanently fixed in position; the problem of providing a mounting for the drive on a domestic sewing machine is not so simple. Such a mounting should be readily secured to all types of hand or foot-operated domestic sewing machines without the use of screws, bolts or other fastening means requiring the services of a mechanic and defacing the machine or its stand. It should be readily removable to permit closing or covering of the machine and yet hold the motor securely in position during use. It is an object of the present invention to provide such a mounting, particularly adapted for use in connection with domestic machines.

The speed of the sewing machine must be under control and this control is commonly effected by varying the speed of the motor by means of a rheostat. The use of rheostats is objectionable for several reasons; they are expensive, they get out of order easily, and they do not, for the most part, give a smooth curve variation in the speed of the motor. I prefer to vary the speed of the machine, not by varying the speed of the motor held in fixed driving relation to the machine, but by varying the driving pressure between the motor and the machine while running the motor at constant speed. This variation in the driving pressure is effected by a controlled bodily movement of the motor relative to the machine. When the drive is a friction drive, the functional contact between the driving pulley of the motor and the hand-wheel of the machine is varied, and where the drive is a belt drive, the tension on the belt is varied. In order to limit the maximum driving pressure it has been proposed to employ the weight of the motor itself for exerting this pressure. This is commonly known as the gravity control and is illustrated in my Patent No.

1,377,018 wherein is described a motor drive for sewing machines in which a motor running continuously at a constant speed is mounted adjacent the machine and constantly urged into driving relation by means of its own weight. This movement, however, is opposed by means of a spring which normally holds the motor in inoperative position and the force of which must be counteracted by the operator to permit the motor to move under its own weight into driving position. The effective driving pressure of the motor and hence the speed of the sewing machine can thus be nicely and easily controlled. It is a more specific object of the present invention to provide a motor mounting suitable for a drive in which the speed of the machine is varied by varying the driving pressure of the motor and particularly adapted for a gravity control drive.

In attaining these objects I have mounted the motor upon a bracket intended to be suspended from the frame of the machine, making use of one of the small openings commonly found in the rear wall of the vertical arm of the machine frame and utilized for assembly purposes. The bracket is provided with a vertically extending hooked arm which enters one of these openings, and a thrust member which bears against the arm below the opening, the moment exerted by the weight of the motor holding the bracket in position. The motor is moved into driving relation with the machine by means of its own weight, but is normally held out of driving relation by means of a spring under the control of the operator.

In the accompanying drawings I have illustrated a preferred embodiment of my invention. In these drawings Figure 1 is a side elevation of the right-hand end of a sewing machine showing a driving motor mounted adjacent the hand-wheel in accordance with the present invention; Figure 2 is a vertical section taken along line 2-2 of Figure 1; Figure 3 is a vertical section taken along line 3-3 of Figure 1 and Figure 4 is a horizontal section taken along line 4-4 of Figure 1. The sewing machine illustrated in the drawings comprises the usual frame 1 having a horizontal arm 2 and a vertical arm 3 extending upward from the table or stand 4. The machine is provided with the usual hand-wheel 5 journaled within the frame. The rear wall of the ver-

tical arm 3 is provided with a plurality of openings 6 permitting access to the interior of the frame and utilized in assembling the machine. I shall now describe the means 5 by which I mount a driving motor in operative relation to the machine.

The motor 7 is arranged with its shaft in a plane with the axis of the rotation of the hand-wheel and generally parallel thereto and with its cone-shaped driving pulley 8 just below the hand-wheel. This motor is pivotally mounted at 9 upon a supporting bracket 10 provided with a yoke member 12 which directly supports the motor and to 15 which the motor is pivotally connected. This yoke member is mounted for vertical adjustment upon a horizontal arm 13 of a thrust member 14 provided with an arcuate face 15 which bears against the vertical end wall of 20 the arm 3. The bracket is completed by means of a vertical arm 16 adjustably secured to the thrust member 14 and terminating in a hooked portion 17 which extends within one of the openings 6 and embraces 25 the lower peripheral edge thereof. The moment exerted by the weight of the motor holds the thrust member and the hooked arm in the positions illustrated in the drawings and thus firmly anchors the motor itself in 30 driving relation to the machine. I shall now describe the manner in which the speed of the sewing machine is controlled by the motor mounted as described above.

Secured to the lower part of the motor 35 housing is a cylindrical casing 18 which houses a compression coil spring 19. The inner end of this coil spring bears against a cap 21 and the outer end against a movable plunger 22 which in turn bears against a depending ear 23 on the bracket. The spring is so designed that acting through the plunger 22 and the ear 23, it opposes the weight 40 of the motor and normally holds it tilted about its pivot in the position illustrated in full lines in the drawing, the driving pulley being thus held out of contact with the hand-wheel as shown. In order to permit the motor to swing downward about its pivot and move the driving pulley into contact with the hand-wheel it is necessary to compress 45 the spring. This is done by means of a Bowden wire 23 under the control of the operator. This Bowden wire comprises the usual casing 25 and inner wire 26. The upper end of the wire 26 is secured to the plunger 22 and the lower end to a treadle 27. The operator by pressing the outer end 50 of the treadle downward exerts a pull on the wire 26 which, acting through the plunger 22, compresses the spring 19, thus overcoming the effectiveness of that spring and permitting the motor to swing its driving pulley 55 into contact with the hand-wheel. The driving pressure exerted by the driving pulley against the hand-wheel can thus be con-

trolled by the operator and the speed of the machine regulated accordingly.

By making the pulley in the form of a truncated cone, with its big end toward the machine, the contact between the rounded periphery of the hand-wheel and the pulley is one of true tangency. As the pressure increases this contact may develop into a small area, but the increase in the effective driving pressure is constant. With the grooved pulley this might not be the case.

The motor drive illustrated and described above is readily positioned relative to the machine by the simple expedient of inserting the hooked end 17 of the bracket into one of the openings 6 and swinging the thrust member into contact with the vertical wall of arm 3. No other securing means are necessary, the weight of the motor holding the bracket securely in place. Removal of the drive can be accomplished quickly and easily. Employing the gravity control principle, the motor can be swung into and out of driving relation to the hand-wheel without in any way interfering with the supporting bracket.

I claim:

1. In a sewing machine having a frame with an opening therein, the combination of a motor support having an arcuate thrust member bearing against the frame, and a vertical arm secured to the support, and having a hook entering the opening in the frame above the thrust member for holding the support suspended upon the frame.

2. In a sewing machine having a hand-wheel and a frame with an opening therein, the combination of a motor support having an arcuate thrust member bearing against the frame, a vertical arm secured to the support, and having a hook entering the opening in the frame above the thrust member for holding the support suspended upon the head, and a motor on the support, the weight of the motor holding the thrust member and the hook firmly in position.

3. In a sewing machine having a frame with an opening therein, the combination of a motor support having an arcuate thrust member bearing against the frame, a vertical arm secured to the thrust member, and having a hook entering the opening in the frame above the thrust member for holding the support suspended upon the frame, a motor pivotally mounted on the support, and a driving pulley on the motor contacting with the lower part of the hand-wheel.

4. In a sewing machine having a frame with an opening therein, the combination of a motor support having an arcuate thrust member bearing against the frame, a vertical arm secured to the thrust member, and having a hook entering the opening in the frame above the thrust member for holding the support suspended upon the frame, a motor pivotally mounted on the support, a

driving pulley on the motor contacting with the lower part of the hand-wheel, and means for swinging the motor about its pivot to vary the pressure of the driving pulley 5 against the hand-wheel.

5. A sewing machine comprising the combination of a frame having a horizontal and a vertical arm, a hand-wheel, an opening in the vertical arm facing the hand-wheel, a 10 motor supporting bracket suspended from the opening in the vertical arm having a thrust member bearing against the vertical arm below the opening, and a motor mounted on the bracket with its center of 15 gravity beyond the thrust member on the side away from the frame, so that the weight of the motor holds the thrust member against the vertical arm.

6. A sewing machine comprising the combination of a frame having a horizontal and a vertical arm, a hand-wheel, an opening in the vertical arm facing the hand-wheel, a 20 motor supporting bracket suspended from

the opening in the vertical arm, a motor mounted on the bracket with its driving pulley in contact with the lower part of the hand-wheel, and means for varying the driving pressure between the pulley and the hand-wheel. 25

7. A motor drive for a sewing machine 30 having a frame and a hand-wheel comprising the combination of a motor supporting bracket, means for suspending the bracket from the frame of the machine, a motor pivotally mounted on the bracket with its driving pulley adjacent the hand-wheel and urged into contact therewith by the weight of the motor, a spring carried by the motor bearing against the bracket and normally 35 tilting the motor so that its driving pulley 40 is out of contact with the hand-wheel, and means under the control of the operator for counteracting the effect of the spring.

In testimony whereof I affix my signature.

HYMAN MAIMIN.
